UNITED STATES PATENT OFFICE.

JAMES R. G. ADDINGTON, OF NICKELSVILLE, VIRGINIA, ASSIGNOR OF ONE-HALF TO
LLOYD C. GILLEY, OF GATE CITY, VIRGINIA.

BORING DEVICE FOR BORING MACHINES.

1,409,354.

Specification of Letters Patent. Patented Mar. 14, 1922.

Application filed May 15, 1920. Serial No. 381,774.

To all whom it may concern:

Be it known that I, JAMES R. G. ADDINGTON, a citizen of the United States, residing at Nickelsville, in the county of Scott and

5 State of Virginia, have invented certain new and useful Improvements in Boring Devices for Boring Machines, of which the following is a specification, reference being had to the accompanying drawings.

10 This invention relates to an improved boring device for boring machines, and an object of the invention is to provide a device of this kind for boring round, square, elliptical and like shaped holes in various materials, and it is a further aim to provide a novel device of this kind which is very simple, efficient and practical in construction, capable of being cheaply made for sale at a reasonable profit.

15 Another object is to provide a device wherein means is provided for boring a round hole, and also including means for squaring the corners, and also means for cleaning out or removing the material from 25 the hole between the square corners and the diametrically opposite portions of the hole at right angles to the square corners, thereby enabling the tool to bore a square hole.

20 Still another object consists in the provision of a boring tool including a main bit, expansive and retracting bits and a plurality of rotary bits which are revolvable in directions at right angles to the plane of movement of the main bit, whereby the 25 square holes may be bored.

25 A further object consists in the provision of a boring tool wherein a single rotating member is instrumental in operating all of the bits, in fact as the main bit is carried by 30 the single revolvable member, the main bit acts to bore a round shaped hole. Since the expansive and retracting bits are carried by the main bit and have operative connections with a stationary head, said 35 retracting and expansive bits are operated radially. Since the bits, which are disposed at right angles to the main bit, are carried by the head and have operative gear connections with the revolvable member, said 40 bits are rotated. The main bit and the expansive and retracting bits and the bits 45 rotative at right angles to the main bit perform their respective boring functions in order to square a round hole or bore other 50 shaped holes.

55 A still further object embodies a boring

device wherein the expansive and retracting bits may have such operative cam or gear connections with the head of the boring device that either a round, elliptical or other 60 shaped hole may be bored, it also being the aim in some instances to provide worm gear connections between the expansive bits and the head, whereby holes of different sizes 65 may be bored.

Additionally the invention aims to provide a tool of this kind wherein various shapes and constructions of bits proper, which are rotatable at right angles to the main bit may be employed, it also being the 70 aim to vary the construction and shape of such bits.

While the design and construction at present illustrated and set forth is deemed preferable, it is obvious that as a result 75 of a reduction of the invention to a more practical form for commercial purposes, the invention may be susceptible to changes, and the right to these changes is claimed, provided they are comprehended within the 80 scope of what is claimed.

The invention comprises further features and combination of parts, as will be herein-after set forth, shown in the drawings and 85 claimed.

In the drawings:

Figure 1 is a view in elevation of a portion of a boring machine post including the chuck, and a stationary frame of the machine, showing the improved boring device 90 as applied to the chuck.

Figure 2 is a bottom plan view of the boring device showing the same in engagement with a hole which has been squared, the material surrounding the hole being in section, 95

Figure 3 is a vertical sectional view through the boring device constructed in accordance with the invention, showing the expansive bits as carried by the main bit and also showing the bits which are rotative 100 in directions at right angles to the plane of movement of the main bit.

Figure 4 is a sectional view on line 4-4 of Figure 3.

Figure 5 is a detail view of a modified 105 form of bit for squaring the corners of a cylindrical hole.

Figure 6 is a rear face view of the bit shown in Figure 5.

Figure 7 is a vertical sectional view 110 through a modified form of boring device,

Figure 8 is a horizontal sectional view on

line 8—8 of Figure 7, showing an elliptical cam groove with which the expansive and retracting bits operatively engage, for the purpose of converting a round hole into an elliptical hole, in fact the main bit will act to bore the hole round while the expansive and retracting bits will act to convert it elliptical in cross section,

Figure 9 is a transverse sectional view 10 through the head of the boring tool showing another form of groove with which bits operatively connect for facilitating the boring of other shapes of holes.

Referring more especially to the drawings, 15 1 designates a portion of a boring machine post and 2 the frame thereof and 3 denotes the boring machine chuck, which carries the boring spindle 4. The lower end of this spindle terminates in a main boring bit 5 20 which is substantially circular as shown, and the under face thereof has a depending spiral threaded leading bit 6 and merging from the thread of this leading bit and in curved directions therefrom are cutting edges 7, 25 which terminate in cutting or lining bits 8. The leading bit 6 acts to take hold in the material which is being bored, the cutting edges 7 acting to remove the surface of the bottom of the hole, in fact shave off the material, while the cutting or lining bits 8 act 30 to gouge into the bottom and at the same time shave the cylindrical surface of the hole.

The upper surface of the main bit 5 is 35 provided with channels 9 which extend in directions offset from the center of the bit and receive expansive and retracting bits 10. These bits 10 are provided with cutting edges 11 which act to gouge the bottom of 40 the hole and during the operations act to remove the material between the square corners of the hole and the diametrically opposite portions of the walls of the hole at right angles to the square corners so as to 45 square the surface of the hole. The bits 10 also have cutting edges 12.

It will be noted that between the cutting edges of the bits 7 and parts of the heads carrying the bits 7 the head of the drilling 50 or boring device is cut away, so that the material or shavings will pass upwardly over the head.

In drilling or boring holes, the bits 8 are arranged, so as to cut incisions in the material, as the cutting edge 7 is cutting the bottom of the hole. These projections or cutting edges are very important, as the bit would clog without them. In fact they cut incisions in the material to be bored prior to the 55 cutting bits or edges 11, and as the main bit begins to cut, the material is left in small narrow strips, which break and crumble up, or fall apart, which are then easily forced upwardly above the main body of the bit 60 or gear case.

The upward projections of the bits 10 as well as those of other bits similar to 10 are provided for the purpose of allowing the bits to have sufficient wearing and cutting surfaces. On account of repeatedly sharpening the bits they become reduced, therefore, it is necessary to have the projections opposite the cutting edges. The bits 10 when cutting the straight sides of the opening being bored or the round opening being 70 squared, travel the greater part of their way on a straight path except where they make the corners of the path of travel hence the lower cutting edges 11 and the cutting edges 75 12 on the ends of the bits 10 act to remove 80 the material from the hole, opening or depression being bored. The rectangular dotted lines shown at the ends of the bits 10 indicate the distance that the bits cut into 85 the material.

The boring device includes a supporting head 13 and the under surface of this head is provided with a cam groove 14. In fact this groove 14 may be either circular, elliptical, or otherwise shaped, for instance as 90 shown in dotted lines in Figure 2. It is obvious that in case the groove 14 is constructed elliptical, the hole to be bored by the bits 10 will be elliptical, the main bit 5 first acting to construct the hole cylindrical. 95 Should the groove 14 be made circular, the hole to be bored by the bits 10 will be circular. However, should the groove 14 be shaped as shown in Figure 2 then the bits 10 are employed to remove the material at 100 points between the square corners and the diametrically opposite portions of the hole at right angles to the square corners, for instance, the material as indicated in dotted lines as at 15 in Figure 2.

In order to retain the bits 10 in place, plates 16 are fitted over the portion 17 of the boring spindle and are secured to the bit 5 by means of screws 18. Also secured by screws 18^a to the main bit 5 are arcuate plates 19, which act to additionally hold the expansive and retracting bits 10 in position. In order to cause the expansive and retracting bits 10 to operate, cylindrical projections 20 extend upwardly from the bits 10 and engage the groove 14, regardless of its shape. It is obvious that as the main bit 5 rotates with the boring spindle and as the head 13 is held stationary it will be seen that the bits 10 will operate outwardly and retract, and according to the shape of the groove 14 the bits 10 will move correspondingly to conform to the shape of the groove, thereby constructing a hole substantially conforming to the shape of the groove. In 120 other words, should the groove 14 be circular the hole will be cylindrical, and if the groove be constructed as shown in dotted lines in Figure 2 the bits 10 will operate to assist in squaring the hole.

The boring spindle operates through the stationary head 13 and the stationary frame 21. The stationary frame 21 is provided with diametrically opposite slots 22, 5 which, as shown in Figure 1 receive projections 23 of the lower end of the frame 21 in order to hold the frame 21 stationary. As the head 13 is rigidly fixed to the frame 21, the head 13 is also held stationary.

10 The head 13 comprises the upper and lower sections and parts 24 and 25, which are secured together by means of the screws 26.

15 At points intermediate the screws 26, the adjacent faces of the sections 24 and 25 of the head 13 have cavities, which, when the sections 24 and 25 are secured together form pockets 27 for the reception of the bevel gears 28. These gears 28 are rotatable with 20 the radial spindles 29, which are mounted in bearings 30 and 31 of the two sections or parts of the head 13. In fact, the gears 28 are threaded on the radial spindles 29 and are additionally secured thereon against rotation. 25 relatively to the spindles by means of the set screws 32. The lower section 25 of the head 13 is provided with a countersink 33 in which the main bevel drive gear 34 is operable for the purpose of driving the pinions 30 or bevel gears 28. The boring spindle above the portion 17 is slightly reduced, and constructed on the reduced portion adjacent the shoulder 35, caused to be formed by reducing the spindle at this point, are threads 36 35 which are engaged by the threads of the main bevel driving gear 34 to assist in holding the gear 34 on the spindle. In order to insure against movement of the main bevel drive gear, a set screw 37 is threaded dia-

40 metrically through the gear and into the spindle, thereby preventing rotation of the gear relatively to the spindle. It is obvious that as the head 13 is stationary with the frame 1 as hereinafter described and since 45 the boring spindle and bit 4 and 5 are rotatable in the head 13, the main bevel drive gear will impart movement to the pinions 28 which will transmit movement to the radial spindles 29.

50 The outer ends of the radial spindles 29 carry rotating bits 38 which are rotative in directions at right angles to the plane of movement of the main bit. These bits 38 act to square the corners of the hole, in fact 55 to remove the material from the corners of a round hole. The bits 38 are fastened to the radial spindles 29 by means of suitable threads as indicated at 39 and through the medium of the set screws 40.

60 The upper section 24 of the head 13 is threaded at 41 to the reduced end of the stationary frame 21. The lower part of the stationary frame 21 has an annular flange 42 which overlies the upper section 24 of 65 the head 13, there being a suitable set screw

or set pin 43 passing through the flange 42 and biting into a portion of the upper section 24 of the head 13 in order to hold the head 13 in proper position relatively to the frame 21 which in turn is held stationary. 70

In boring holes, whether they be round, elliptical, square or otherwise shaped, the frame 21 is first set and as the head 13 is carried by the frame 21 the head 13 is likewise set. Movement is then imparted to the 75 boring spindle, which in turn transmits movement to the main bit 5 and through the medium of the groove 14 the bits 10 will be actuated, whereas through the movement of the main gear 34, the radial spindles 29 are 80 operated thereby acting to square round holes, or otherwise shape them, it depending entirely upon the construction of the groove 14, and entirely upon the means for causing expansive and retracting movements of the 85 bits 10. The gears 28 are threaded upon the shafts 28, as well as being secured by keys as shown.

A circular ring plate 44 is fitted down upon the main gear 34 to act as a bearing for 90 the gear and this ring plate 44 has diametrically opposite bearings 45, semi-circular in cross section for the reception of the inner ends of the rotative radial spindles 29.

In the operation of the tool as constructed in Figure 3, the leading or biting bit 6 acts to burrow into the material; and at the same time retain the boring apparatus to its work. The cutting edges 7 act to shave the bottom of the hole at a point from the cut formed by the leading bit 6, while the bits 8 act to gouge into the bottom of the hole, and assist materially with the cutting edge 7, to remove the material from the hole. 100

In Figure 5 another form of corner bit is 105 shown and in this case the bit is constructed in the form of a worm or screw shape and such bit 48 comprises a body having a spiral helical cutting edge 49 while the terminal of the body of the head has a sharp cutting or tapering or leading bit 50. The face of the body of the bit 48 opposite the leading or tapering bit 50 is provided with a plurality of teeth 47, which act to throw the shavings upward when the shavings are 110 thrown against the teeth by the main cutting bit.

In the drawings, Figure 7, it will be seen that the particular form of head 13 is eliminated and in its stead a head 51 is employed. This head 51 may have on its under surface any shape of cam groove, it depending entirely upon the construction of hole to be bored. In the present instance, the head 51 has an elliptical groove 52, but in Figure 120 9 the head 51 is formed with a groove 53, similar to the groove 14. In the first instance, the expansive and retracting bits will form a hole which is elliptical. In the second instance, the head of the boring de- 125 130

vice has a substantially angular groove in which case the bits 10 will cut a correspondingly shaped hole. The head 51 is held stationary to the frame 62 by means of the 5 projections 23^a and the slot 22, which is formed in the stationary frame 21. In fact, when the head 13 is removed for the purpose of attaching the head 51, the frame 21 is reattached so that the reduced threaded 10 portion 41 of the frame 21 will screw into the head 51 thereby holding it stationary with relation to the frame 21 as by means of the head or holding screw 54.

In Figure 7 of the drawings a different 15 form of frame is provided. This frame 62 is stationary in which the frame 21 is guided. In other words, the frame or arm 62 has an opening through which the frame or pipe 21 passes. This frame or pipe 21 20 moves through the opening and downwardly as the boring or drilling is accomplished, which is similar to the action of the frame 2 shown in Figure 1. In Figure 1 the frame 2 is stationary and acts as means to 25 guide the frame or tube or pipe 21 as it moves downwardly, through the medium of the engagement of the projections 23 operating in the slots 22.

The invention having been set forth, what 30 is claimed as new and useful is:—

1. In a boring tool, a stationary frame having a head, a revolute spindle operable therein and carrying a main bit, additional bits movable with and carried by the main 35 bit and having operative connections with the head for moving the additional bits in directions offset from the center of the main bit and beyond its periphery, a plurality of auxiliary spindles mounted in the head radially 40 thereof and having operative connections with the spindle, and auxiliary bits carried by the auxiliary spindles, for cleaning out and squaring the corners of a round hole.

45 2. In a boring tool, a stationary frame having a head, a spindle revolute therein and provided with a main bit having guides, additional bits carried by and movable with and in said guides of the main bit, said additional bits being immediately between the head and the main bit and having cam connections with the head for causing them to move in directions offset from the center of the main bit and beyond the periphery of 50 the main bit, for constructing holes of different shapes in cross section.

3. In a boring tool, a stationary frame having a head, a spindle revolute therein and provided with a main bit, additional 60 bits carried by and movable with the main bit, said additional bits having cam connections with the head for causing the additional bits to move in directions offset from the center of the main bit and beyond the periphery of the main bit, for constructing 65

holes of different shapes in cross section, a plurality of auxiliary spindles mounted radially in the head and provided with auxiliary bits for boring out the diametrically opposite portions of a round hole to square 70 the same, and operative connections between the auxiliary spindles and the main spindle, to impart movement thereto.

4. In a boring tool, a stationary frame having a head detachably connected thereto, said head comprising two sections and provided with pockets, a main spindle revolute in the frame and carrying a main bit adjacent the lower part of the head, a gear fixed on the main spindle, a plurality of auxiliary spindles mounted radially in the head and operatively connected to said gear, whereby movement is imparted to the radial spindles, auxiliary bits carried by the auxiliary spindles, expansive and retracting 80 bits carried by the main bit and having operative connections with the head, whereby the additional bits are moved in directions offset from the center of the main bit.

5. In a boring tool, a stationary frame having a head connected thereto, said head comprising upper and lower sections and having pockets, a main spindle revolute in the frame and having a main bit at its lower end, a plurality of auxiliary spindles 90 mounted radially in bearings of the head at points between the two sections and provided with pinions operative in the pockets, auxiliary bits carried by the auxiliary spindles, a main gear fixed on the main spindle 100 and engaging the pinions for imparting movement to the auxiliary spindles, additional bits carried by the main bit in a revolute direction with the main bit and having cam operative connections with the head, 105 whereby as the spindle and the main bit rotate, the additional bits may move in directions beyond the periphery of the main bit in planes offset from the center of the main bit.

6. In a boring apparatus, a stationary frame having a head, a main spindle mounted in a bearing of the frame and having a main bit below the head, the upper face of the bit having channels extending in directions offset from the center of the main bit, auxiliary bits movable in said channels, a ring plate surrounding the base of the spindle and interposed between the head and the main bit and secured to the main bit, thereby 115 covering the inner ends of the channels, a ring surrounding the head and secured to the upper face of the main bit, thereby covering the outer portions of the channels, and retaining the auxiliary bits slidably in the 120 channels, and operative connections between the auxiliary bits and the undersurface of the head for extending the auxiliary bits beyond the periphery of the main bit.

7. In a boring apparatus, a stationary 125

- frame having a head, a main spindle mounted in a bearing of the frame and having a main bit below the head, the upper face of the bit having channels extending in directions offset from the center of the main bit, auxiliary bits movable in said channels, a ring plate surrounding the base of the spindle and interposed between the head and the main bit and secured to the main bit, thereby covering the inner ends of the channels, a ring surrounding the head and secured to the upper face of the main bit, thereby covering the outer portions of the channels, and retaining the auxiliary bits slidably in the channels, and pin and channel connections with the undersurface of the head for extending the auxiliary bits beyond the periphery of the main bit.
8. In a boring apparatus, a stationary frame having a head, a main spindle mounted in a bearing of the frame and having a main bit below the head, the upper face of the bit having channels extending in directions offset from the center of the main bit, auxiliary bits movable in said channels, a ring plate surrounding the base of the spindle and interposed between the head and the main bit and secured to the main bit, thereby covering the inner ends of the channels, a ring surrounding the head and secured to the upper face of the main bit, thereby covering the outer portions of the channels, and retaining the auxiliary bits slidably in the channels, and operative connections between the auxiliary bits and the undersurface of the head for extending the auxiliary bits beyond the periphery of the main bit.
- 30 35 40 45 50 55 60 65
9. In a boring apparatus, a stationary frame having a head, a main spindle mounted in a bearing of the frame and having a main bit below the head, the upper face of the bit having channels extending in directions offset from the center of the main bit, auxiliary bits movable in said channels, a ring plate surrounding the base of the spindle and interposed between the head and the main bit and secured to the main bit, thereby covering the inner ends of the channels, a ring surrounding the head and secured to the upper face of the main bit, thereby covering the outer portions of the channels, and retaining the auxiliary bits slidably in the channels, and pin and channel connections with the undersurface of the head for extending the auxiliary bits beyond the periphery of the main bit.
- 10 15 20 25 30 35 40 45 50 55 60 65
10. In a boring apparatus, a stationary frame having a head, a main spindle mounted in a bearing of the frame and having a main bit below the head, the upper face of the bit having channels extending in directions offset from the center of the main bit, auxiliary bits movable in said channels, a ring plate surrounding the base of the spindle and interposed between the head and the main bit and secured to the main bit, thereby covering the inner ends of the channels, a ring surrounding the head and secured to the upper face of the main bit, thereby covering the outer portions of the channels, and retaining the auxiliary bits slidably in the channels, the undersurface of the head having a cam channel, said auxiliary bits having projections operative in said cam channel, whereby as the main spindle is rotated, the auxiliary bits are extended beyond the periphery of the main bit.
- 15 20 25 30 35 40 45 50 55 60 65
11. In a boring tool, a boring spindle having a main bit, a stationary frame in which the spindle revolvably operates, said main bit having guides substantially diametrically opposed, expansive and retracting bits movable in the guides, and cam connections operatively connecting the frame and the bits and being in close position to the spindle and frame and overlying the bits, whereby the expansive and retracting bits may move outwardly and inwardly for producing irregular boring.
- 100 105 110 115 120 125 130
12. In a boring tool, a boring spindle having a main bit, a stationary frame in which the spindle revolvably operates, said main bit having guides substantially diametrically opposed, expansive and retracting bits movable in the guides and having cam connections with the frame, whereby the expansive and retracting bits may move outwardly and inwardly for producing irregular boring, additional bits mounted in the frame and extending in planes radially from the spindle and at angles to the expansive and retracting bits for boring out all corners of the bore, and operative connections between the additional bits and the spindle for imparting motion thereto.
- 120 125 130
13. In a boring apparatus, a stationary frame having a head, a main spindle mounted in a bearing of the frame and having a main bit below the head, the upper face of the bit having channels extending in direc-

tions offset from the center of the main bit, auxiliary bits movable in said channels, a ring plate surrounding the base of the spindle and interposed between the head and the main bit and secured to the main bit, thereby covering the inner ends of the channels, a ring surrounding the head and secured to the upper face of the main bit, thereby covering the outer portions of the channels, and retaining the auxiliary bits slidably in the channels, and operative connections between the auxiliary bits and the under surface of the head for extending the auxiliary bits beyond the periphery of the main bit, the construction and arrangement of said operative connections being such that as the spindle revolves, the last mentioned bits may move outwardly and inwardly in planes at right angles to the rotation of the main bit, whereby the cylindrical boring may be followed

up with angular boring, and means mounted in the frame radially of the spindle for boring the corners of the bore.

14. In a boring tool, a spindle, a main bit thereon and provided with guides, additional bits carried by and movable in the guides of the main bit, a stationary frame having a head in which said spindle is revolvably mounted, whereby the head may overlie the guides and said additional bits, and means immediately between and operatively connecting the head and the additional bits and causing them to move in directions toward and beyond the periphery of the main bit, for constructing bores of different shapes in cross section.

In testimony whereof I hereunto affix my signature.

JAMES R. G. ADDINGTON.
